UNITED STATES PATENT OFFICE.

JOHN F. STEWARD, OF CHICAGO, ILLINOIS.

LUG FOR TRACTION-WHEELS.

1,114,714.

Specification of Letters Patent.

Patented Oct. 20, 1914.

Substitute for application Serial No. 684,501, filed April 23, 1912. This application filed November 8, 1913. Serial No. 799,982.

To all whom it may concern:

Be it known that I, JOHN F. STEWARD, a citizen of the United States, residing at Chicago, in the county of Cook and State of Illinois, have invented certain new and useful Improvements in Lugs for Traction-Wheels, of which the following is a full description, reference being had to the accompanying drawings, in which—

10 Figure 1 represents a segment of the rim of a traction wheel showing my lugs in the three positions which they are adapted to occupy relative thereto, at the will of the operator; Figs. 2, 3 and 4 are sectional end 15 elevations of the same lugs, showing them in each of the three positions in which they may be placed upon the rim of the wheel.

The object of the invention is to provide a single lug that may have various degrees 20 of aggressiveness upon the soil, either by conformation or by radial height, or in fact, both. Stated in the simplest terms, my lug may be considered as triangular, having a base, a perpendicular and a hypotenuse. 25 They may be forged from angle iron, but I prefer to make them of malleable cast iron.

A may be considered to represent the lug as a whole, a the base of the triangle, a^1 the perpendicular of the triangle, and a^2 the 30 hypotenuse of the triangle.

B represents a section of the rim of a traction wheel, and C one of the bolts adapted to secure the lugs to the rim of the wheel, preferably having the T-head c and 35 the nut c^1 .

Although the lugs may be treated as substantially triangular, variations therefrom may be made without departing from the invention, so long as multiple radial heights 40 or multiple variations in aggressiveness are attained.

The lugs are provided, preferably near their ends, with one or more bolt holes, but I have chosen to so adapt a single bolt hole 45 for each bolt that will permit the lug to be placed in either of the three positions upon the rim of the wheel to which it is adapted.

Turning to Fig. 2, it will be seen that the hypotenuse, of the form I have considered 50 preferable, lies upon the rim B of the wheel. The bolt being T-headed, the wings thereof, in effect, rest upon a part of each of what I have considered the base and the perpendicu-

lar of the triangle. The nut c^1 tightly drawn, the bolt becomes competent to hold the lug in place. It is plain that a single common bolt might be substituted and merely pass through the lug at the junction of the base and perpendicular, but by providing the specific construction of aperture for the bolt, I accomplish very beneficial results, as will be seen by reference to 2 of Fig. 1, and in Fig. 3, where the bolt is turned so that its T-head may be longitudinal relative to the lug, in effect passing through only the base of the triangle; while in Fig. 4 the bolt, its T-head also placed longitudinal relative to the lug, passes through the vertical portion of the triangle. My preferred form, then, is to make what are, in effect, three bolt 70 holes, in fact, a single opening, by slotting through a portion of the base and a portion of the perpendicular, as shown in Fig. 2. When placed as in Figs. 3 and 4, it is only necessary to loosen the nut c^1 , when the lug 75 may be tipped so as to rest with either its base or the perpendicular on the rim of the traction wheel. It is thus seen that the time and labor required to change from the positions shown in Figs. 3 and 4 is not necessarily great. For light road work the lug shown in position 1 of Fig. 1 is best adapted to the requirements; for soft soil the position shown in 2 of Fig. 1 is preferable, and in soil still softer the position shown in 3 of Fig. 1 is preferable. In Fig. 1 the hypotenuse resting upon the rim of the wheel, the lug is not adapted to dig into the surface of roads and injure them. In 2 of Fig. 1, with the perpendicular resting upon the rim of the wheel, the lug is best adapted for travel over fields, as in plowing, while, when resting upon the base, as in 3 of Fig. 1, the lug is best adapted for passing over soft plowed ground in case the tractor, to the wheels of which these lugs are especially adapted, is pulling, say, seeders or peg tooth harrows.

While the drawings show a strictly right-angle triangular lug, in section, it is evident that a small departure therefrom may be made without departure from the actual invention here shown and claimed, so long as the prism-like form, or L-shaped section, is maintained. The lugs may extend partly or wholly across the rim of the wheel, as desired.

The flanks of the triangular lugs are curved to fit upon the rim of the wheel, whichever of the sides selected as a base.

What I claim as my invention, and desire to secure by Letters Patent, is:

1. A variable-in-height traction wheel lug, of substantially right angular form, in section, adapted to transverse alinement across the rim of the wheel, two or more of its faces adapted to lie against the rim of the wheel and the lug there suitably secured.
2. A variable-in-height substantially triangular lug for traction wheels, the sides thereof of unequal width, each of said sides adapted to lie against the rim of the wheel, and the lug there suitably secured.
3. A substantially triangular lug for traction wheels, the sides thereof of unequal widths, each side adapted to lie upon the rim of the wheel, and means for transverse securement of the lug thereto, whichever of the sides of the lug may have been chosen as a base.
4. A substantially triangular lug for traction wheels, the sides thereof of unequal widths, each side adapted to lie upon the rim of the wheel, and means in common for transverse securement to the rim of the

wheel, whichever side of the lug may have 30 been chosen as a base.

5. In combination, a lug, a wheel rim and a T-head bolt for securement of the lug to the rim, the lug adapted to receive the T-head bolt with its lateral extensions 35 transverse to the said lug or longitudinally relatively thereto.

6. In combination, triangular lugs and a traction wheel rim, said lugs having unequal sides and variable in radial height 40 from the rim of the wheel by means of selective sides provided to serve as bases for securement of the lugs to place.

7. In combination, a substantially triangular lug, a wheel rim, the sides of the lug 45 of differing widths, two or more of the sides of the lug adapted to lie against the rim, and a bolt, the head of the bolt and the aperture in the lug so adapted to each other that the bolt may serve to secure the 50 lug to the rim, regardless of which side of the lug may have been selected to serve as a base.
